UNITED STATES PATENT OFFICE.

JEROME B. SHAW, OF BROOKLYN, ASSIGNOR TO JACOB T. CAMMEYER, OF NEW YORK, N. Y.

DESIGN FOR LEGAL BLANKS.

Specification forming part of Design No. 5,972, dated July 2, 1872.

Specification describing a Design for Law Blanks, such as deeds, bonds, mortgages, &c., invented by JEROME B. SHAW, of the city of Brooklyn, in the county of Kings and State of New York.

A represents a figure at the left-hand corner of the top of first page. This figure is designed or intended to represent a legal gentleman in his office, sitting at his desk, with the emblem of justice over his head and his client standing at the rear of his desk. Still in the rear is shown a library. This part of my design is surrounded by a border in the form of an ellipsis. Underneath this border is a Bible, upon which lies the sword and pen. At the left hand, lower corner, is a package of envelopes, and at the center, on each side of the ellipsis, are also packages of envelopes. At the top or crown of the ellipsis is an hour-glass, representing time, and on each side of this are the wands of Mercury; and still to the right of this is the Goddess of Liberty, while at the left is a prisoner in chains.

What I claim as my invention, and desire to secure by Letters Patent of the United States, is—

A design for the ornamental heads of a set of legal blanks, consisting of the figure at the top or left-hand upper corner of page 1, in connection with the ornamental surroundings, substantially as herein shown and described.
